(57) **CLAIM**

We claim the ornamental design for a door assembly for a vehicle, as shown and described.

DESCRIPTION

FIG. 1 is a right front perspective view showing the new design for a door assembly for a vehicle;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines showing portions of the door assembly, as well as environment, form no part of the claimed design.

1 Claim, 7 Drawing Sheets
